UNITED STATES PATENT OFFICE.

JACOB KOENIG, OF JERSEY CITY, NEW JERSEY.

DESIGN FOR A NICHE OR SHRINE.

No. 39,822.

Specification for Design.

Patented Feb. 16, 1909.

Application filed November 18, 1908. Serial No. 463,326. Term of patent 7 years.

To all whom it may concern:

Be it known that I, JACOB KOENIG, a citizen of the United States, residing at Jersey City, in the county of Hudson and State of New Jersey, have invented a new, original, and ornamental Design for a Niche or Shrine, of which the following is a specification, reference being had to the accompanying drawing, forming part thereof.

The figure is a plan view of a niche or shrine, showing my new design.

I claim:

The ornamental design for niche or shrine, as shown.

JACOB KOENIG.
